UNITED STATES PATENT OFFICE.

OYSTEIN JACOBSEN, OF DAYTON, OHIO, ASSIGNOR TO THE DURIORON COMPANY, INC.,
A CORPORATION OF NEW YORK.

CENTRIFUGAL PUMP.

Application filed April 23, 1928. Serial No. 272,219.

The invention relates to a self-priming construction as applied to a centrifugal pump, and has for its primary objects the provision of an improved structure of the character 5 specified, which is simple in construction and positive in operation; which will bring the pump into operation quickly, and whose effect upon the pump after it is in normal operation, tending to reduce its efficiency, is 10 negligible. One embodiment of the invention is shown in the accompanying drawings, wherein:

Figure 1 is a rear elevation of the pump. Fig. 2 is a rear elevation of one of the castings comprising the pump casing. Fig. 3 is a 15 section on the line III—III of Fig. 1. And Fig. 4 is a side elevation of the complete apparatus on a smaller scale.

Referring to the drawings, 1 and 2 are parts 20 of the pump casing bolted together, as indicated in Fig. 4; 3 is the motor whose shaft 4 carries the impeller or runner 5; 6 is the suction pipe; 7 is the priming inlet to the chamber in the casing 2; and 8 is the discharge 25 pipe.

Extending tangentially from the volute 9 (Fig. 2) is the discharge passage 10, and connected to the side of this passage 10 is a passage 11 leading to the nozzle 12, such nozzle 30 constituting a part of the casting 2 and directed through the passage 13 at the center of the runner 5.

When the pump is primed, the liquid lies at the level *a* filling the elbow 14 and the volute. 35 The pump is then started, and the action of the runner withdraws the liquid in the elbow 14 until it reaches the level marked *b*, the liquid thus withdrawn being forced through the passage 10 and up into the discharge pipe 8 until it reaches a level several feet above the starting level *a*. When this condition is 40 reached, a gradual flow of liquid will occur by gravity through the passage 11 and nozzle 12. The liquid thus supplied at the center of the runner will be forced into the volute 9 and up again into the discharge pipe 8. The discharge from the nozzle to the runner will 45 carry with it air from the elbow 14, which, in a short time, will be exhausted to a degree of 50 vacuum such as to cause it to completely fill with liquid from the pipe 6, thus completing the priming operation.

As soon as this complete flow occurs, the velocity of the liquid in the volute passage 9 and in the passage 10 will have reached a 55 point so high that there is very little pressure in such passage, and as a result, there is little tendency of the liquid to flow through the passage 11 and nozzle 12 under these conditions. After the pump is well started, therefore, the amount of short circuiting through the passage 11 and nozzle 12 is negligible. It will be understood that the conformation of the passage from which the passage 11 takes off is such that at this point of take off, the 60 velocity of the liquid flowing to the outlet 10 is substantially equal to the so-called absolute velocity of the runner, the kinetic energy incident to this velocity being gradually transformed into pressure at reduced velocity in 65 the outlet pipe. The passage 11 preferably takes off the outlet 10 just above the volute, but may take off at any point below the level to which the priming water is raised. The 70 pressure and velocity of the liquid in the outlet up to this level is (during normal operation of the pump) substantially the same as that at the point at which the passage 11 actually takes off, and as a result there is only a slight tendency to cause a circulation through 75 the pipe 12. The efficiency of the pump is therefore only slightly reduced by the self-priming feature of construction.

What I claim is:

In combination in a centrifugal pump, a 80 casing having an inlet eye at its center and a volute around its periphery with an upright discharge passage leading therefrom, a runner or impeller mounted for rotation in the casing with its axis of rotation in line with 85 said inlet eye, a suction elbow with an enlarged end cavity in opposition to and surrounding said inlet eye, a circulation port in the casing leading from the discharge passage above the volute, and a pipe leading from 90 said port and down through said cavity with its end turned laterally in alignment with the axis of the runner in opposition to said eye so that the discharge therefrom through the 95 eye is surrounded by the liquid in the cavity. 100

In testimony whereof, I have hereunto subscribed my name this 20th day of April, 1928.

O. JACOBSEN.
